LOOSE-LEAF BINDER

Joel W. Ostrander, Chicago, Ill.

Application April 29, 1939, Serial No. 270,854

3 Claims. (Cl. 129—17)

This invention relates to loose-leaf binders, and more particularly to what is known in the trade as "metals" for such binders.

The primary object of the invention is to provide a loose-leaf binder of substantial size having a rigid back-member to which the cover members and prong-members may be hinged and will permit the use of prong-members having a relatively large radius of curvature. The relatively flat curvature of the prong-members enables the ledger sheets to be drawn by the prongs in close proximity to the rigid back-member when the book is in closed position.

A further object of the invention is to provide opposed sets of overlapping prong-members of a proper curvature so that when the prongs are moved into overlapping position the divergence between the opposed sets will be kept at a minimum and sufficiently small to impale the perforations in the ledger sheets which may be of either round or oval contour.

A further object of the invention is to provide a simple and improved linkage for moving the opposed sets of prongs simultaneously and permitting them to be locked in either closed, partially opened, or fully opened position. The partially opened position is particularly useful when it is desired to make entries on a sheet in the book without removing the sheet from the binder.

Heretofore, it has not been practical to use a loose-leaf binder of this type in the larger sizes, i. e., over 2 inches, and in the large sizes the arcuate prongs had to be of excessive size and various cam arrangements were required to operate the prongs so that the rigid back-member could not be used conveniently.

The invention is illustrated in a preferred embodiment in the accompanying drawings, in

Figure 1 is a plan view of the mechanism with the covers removed; Figure 2 is a longitudinal sectional view, taken as indicated at line 2 of Figure 1; Figure 3 is a transverse sectional view, taken as indicated at line 3 of Figure 1, showing the prongs in closed position; Figure 4 is a view similar to Figure 3 showing the prongs in fully opened position and the dotted lines indicating the partially opened position; Figure 5 is a fragmentary plan view showing the end of the latching bar in unlocked position; Figure 6 is a sectional view, taken as indicated at line 6 of Figure 1; and Figure 7 is a broken elevational view of the rotor with its pitmans journalled on the upturned end of the rigid back-member.

In the embodiment illustrated A designates a rigid metal back-member provided at its end portions with upturned end standards A'; B, cover-supporting members which are hinged to the backing-plate A and provide supports for the arcuate prong-members B'; C, link mechanism, including a rotor C', for moving the cover-supporting members uniformly towards and away from each other; and D, a locking device for locking the mechanism in a desired adjusted position.

The back-member A comprises a rectangular piece of sheet metal having its end portions struck upwardly to provide the perpendicular standards A' upon which the linkage C may be mounted.

The cover-supporting members B may also be made of sheet metal and are hinged to the back plate, as indicated at 8. The arcuate prong-members B' are permanently and rigidly connected to the cover-supporting members B, as indicated at 9, by riveting or any other suitable manner. The radius of curvature of the prongs B' is an extremely important feature of the invention and must be carefully apportioned to the distance between the hinges 8 so that there will be a minimum amount of divergence between the shanks of the opposed prongs as they are moved from the dotted position shown in Figure 4 to the closed position indicated in Figure 3. A table of preferred sizes is given below.

Any suitable linkage may be provided to cause the prongs to move uniformly from the opened position shown in Figure 4 to the overlapping complementary position shown in Figure 3. The linkage C, which is illustrated, comprises a notched wheel 10 which is journalled on a pivot member 11 on the standard A' and carries pivots 13 to form opposed cranks. A pair of links or pitmans 12 is connected to the notched wheel, as indicated at 13, and their opposite ends are pivotally connected with the cover-supporting members B, as indicated at 14. Thus, it will be understood that if either of the cover-supporting members is swung outwardly, the companion member will move in the opposite direction at the same time and to the same extent. As loose-leaf binders of this type are particularly adapted for use in large ledgers, it is generally preferred to provide duplicate linkages at each end of the back-ing-member.

The locking mechanism D comprises a flat bar provided at one end with a finger piece 16 which may be thrust inwardly to release the link-

ages. A pair of keepers 17 may be struck inwardly from the back-member and serve to confine the bar 15. A tension spring 18 is disposed between one of the keepers and a fastener 19 on the latching bar. A set screw 20 limits the outward travel of the latching bar under the influence of the spring 18. The bar is shown provided at its end portion with cut away portions 21 so that when the bar is thrust inwardly, it will 10 not engage the notched wheels 10. If the bar is released, the prongs may be opened until the latch slips back into one of the notches provided in the wheels 10 and this prevents further movement of the prong-members. Three notches in 15 the wheels 10 are sufficient to enable the operator to lock the device in either its fully opened position, its partially opened position, or its closed position, as desired.

It will be readily understood that each set of 20 prongs may comprise two or more. For the purpose of illustration only two complementary sets have been shown. These prongs are each semi-circular in cross-section and cooperate to provide a practically round prong. If preferred, a ledger 25 sheet having more than two sets of perforations may be employed and any desired number of prongs can be used. It is not essential that the prongs make slidable engagement with each other as shown in Figure 1. However, if the arrangement 30 illustrated is used, it is desirable to have the prongs in one set engage the extreme outer edge portions of the perforations at both ends of the ledger sheet, and the opposite set of prongs engage the inner edge portions of the same perforation. This arrangement serves to hold the sheets 35 in better alignment.

As indicated above, the arc of curvature of the prong must be carefully worked out for a desired size of binder, so that when the prongs are moved 40 to overlapping relation, there will be a minimum amount of divergence. If proper sizes are employed, the points of the prongs will be in perfect registry when they meet, as indicated by the dotted lines in Figure 4, will move slightly out of 45 registration as they are further overlapped, will then again move into perfect registration, and will finally move slightly out of registration, as indicated in Figure 3. By using the proper curves the maximum amount of divergence can be kept 50 so small as not to interfere with the successful use of the device. In a binder of 1-inch size, the divergence will not be over $\frac{1}{64}$ of an inch. In a 4-inch binder, the maximum divergence may be $\frac{1}{8}$ inch. Probably the most useful sizes are the 55 2-inch and 3-inch sizes. The ordinary ring type binders operate satisfactorily in smaller widths.

The following table gives the relative sizes for 60 a number of binders. Figures for intermediate sizes may be worked out readily by laying out to an enlarged scale on a drafting board the desired size of the binder and selecting the radius of curvature which gives the least amount of divergence in any overlapping position of the prongs. The figures below allow for a distance between 65 the center of the hinge 8 and the center where the prong is attached to the cover-supporting member of $\frac{1}{32}$ of an inch. This will accommodate ledger sheets with the usual marginal distance between the perforations and the inner edge of 70 the sheet. For ledgers of the following widths

it is recommended that the prongs have the radius of curvature as indicated.

Book	Radius of arc	Maximum divergence	
1"	$1\frac{1}{16}$ "	$\pm$ or $-\frac{1}{64}$ "	5
$1\frac{1}{8}$ "	$1\frac{1}{16}$ "	$\pm$ or $-\frac{1}{32}$ "	
2"	$1\frac{1}{16}$ "	$\pm$ or $-\frac{1}{64}$ "	
3"	$1\frac{1}{16}$ "	$\pm$ or $-\frac{1}{128}$ "	
4"	$2\frac{1}{4}$ "	$\pm$ or $-\frac{1}{8}$ "	10

It is preferred to have a prong of a length which will extend towards the cover-supporting member on the opposite side to a distance equal to the maximum divergence indicated above for each size. For example, the prongs in a 4 inch binder should have their points $\frac{1}{8}$ of an inch from the cover-supporting member, when the device is closed. If desired, the pins may be tapered longitudinally from a small diameter at their point to a larger diameter at their base. The amount of taper will be sufficient to compensate for the divergence and thus the opposed tapered prongs will remain in alignment in the various overlap positions.

The foregoing detailed description has been given for clearness of understanding only, and no unnecessary limitations should be understood therefrom, for some modifications will be obvious to those skilled in the art.

I claim:

1. A loose-leaf binder comprising: a rigid back-member; two opposed complementary sets of arcuate prong-members hinged to opposite lateral edge portions of said back-member; linking means comprising a notched wheel provided with a pair of opposed cranks which are connected to the sets of prong-members by means of pitmans so that both sets must move simultaneously from open to overlapped position; and a spring held latch for engaging a selected notch in said wheel and releasably controlling the degree of opening of said sets of prongs.

2. A device as specified in claim 1, in which the wheel has a notch for locking the sets of prongs in closed position, a notch for locking said sets in opened position, and an intermediate notch for holding the tips of the prongs in partially overlapped position.

3. A loose-leaf binder comprising: a substantially rectangular metal back-member having its integrally formed opposed end portions turned inwardly to form standards; a pair of cover-supporting members hinged to the opposite lateral edge portions of said back member; two sets of complementary arcuate prong-members rigidly fixed to said cover-supporting members in opposed relation so that the ends of the prong-members of each set will extend into close proximity to the cover-supporting member of the companion set, when the prongs are in interleaved closed position; means on each of said standards for linking the cover-supporting members together so that the prongs of both sets swing uniformly from opened to interleaved position, including a rotor provided with at least three locking notches, a pair of opposed cranks, and pitmans connecting said cranks to the cover supporting members; and locking means for latching said rotor in a desired position.

JOEL W. OSTRANDER. 70
